PNEUMATIC CONTROL ACCELERATING PUMP

Gaston Griffon, Neuilly-sur-Seine, France, assignor to Societe Anonyme Solex, Neuilly-sur-Seine, Seine, France, a society of France

Application July 21, 1945, Serial No. 606,335
In France October 4, 1944

4 Claims. (Cl. 261—34)

1

The present invention relates to pneumatic control accelerating pumps for use in connection with carburetors for internal combustion engines, of the type described in the French patent application No. 862,794, filed January 8, 1940, by Societe Anonyme Solex. The operation of these pumps is controlled by the vacuum existing in the induction passage leading to the engine, especially on the downstream side of the carburetor throttle means so as automatically to obtain the introduction of a given amount of additional fuel into said passage during picking up periods and, if so desired, an increase of the percentage of fuel in the fuel mixture when the pressure in said passage exceeds a given value.

Accelerating pumps of this kind have advantages over mechanically operated pumps but their drawback is that, when the engine is stopped, they discharge the amount of fuel present therein into the induction passage. This is due to the fact that when the throttle is close to the position corresponding to idling of the engine and when said engine is not yet stopped, the depression is maximum and causes the pump body to be filled with fuel. As soon as the engine is stopped, the depression ceases to act and the pump discharges its contents into the carburetor and therefore into the induction passage, which involves serious difficulties when the engine is to be subsequently started.

The object of the present invention is to obviate this drawback.

Other objects of my invention will result from the following detailed description of some specific embodiments thereof with reference to the appended drawings, given merely by way of example, and in which:

Fig. 1 is an axial vertical view of a carburetor provided with a pneumatic control accelerating pump made according to a first embodiment of the invention;

Fig. 2 is a similar view of another embodiment.

In the examples illustrated by the drawings, the carburetor includes a body 1, a throttle valve 2, and a well 3 communicating with the venturi through holes 4. In this well is axially disposed a perforated tube 5 provided at its end with a calibrated orifice 6. Well 3 communicates through a conduit 7 provided with a calibrated orifice 7¹, with a constant level chamber 8 or any other equivalent feed device. Chamber 8 also feeds fuel to the accelerating pump through an orifice 8¹ provided with a valve or ball 8².

The pump includes a portion 9 separated from a portion 10 by a diaphragm 11 or the like. This diaphragm is subjected to the influence of two opposed forces, to wit that of a spring 12 which

2

tends to move it toward the left and that exerted by the depression existing on the downstream side of throttle 2, and which is transmitted to said space 10 of the pump through a conduit 13. 5 This suction tends to move the diaphragm 11 toward the right.

Diaphragm 11 carries a valve 14 which is applied upon its seat when the diaphragm is moved toward the right.

10 Valve 14 is adapted to open or close the communication between chamber 9 and a discharge space 15 from which fuel is fed into the delivery conduit 16 of the pump, this conduit including a calibrated orifice and opening into the venturi of the carburetor.

15 According to my invention, discharge space 15 is connected, through a by-pass conduit 18 with the reserve of fuel constituted by the constant level chamber 8, and, in this conduit there is provided a valve, preferably constituted by a ball 19, which is operatively connected with throttle 2 in such manner that said valve is opened, that is to say ball 19 is away from its seat, when said throttle is in the position corresponding to idling of the engine, or close to this position, while it is closed, that is to say ball 19 is applied against its seat, for all other positions of said throttle.

20 In the embodiment of Fig. 1, delivery conduit 16 communicates permanently with space 15. I 30 make use of a push piece 20, subjected to the action of a spring 21 through the intermediary of a rod 22 connected by means of a lug 23 with push piece 20. Rod 22 is axially slidable in a passage 24 provided in the body 1 of the carburetor. 35 Push piece 20 applies valve 19 against its seat when throttle 2 is in a position intermediate between the fully opened position and a position close to that corresponding to idling of the engine. On the contrary, when throttle 2, under 40 the effect of its controlling means, is closer to said idling position or is in this last mentioned position an arm 25 provided on the pivot spindle of the throttle and moved in the direction of arrow A, comes into contact with sliding rod 22 45 and pushes it, together with push piece 20, which is interconnected therewith, in the upward direction, which releases ball 19. Under the pressure of the liquid from the pump, said ball 19 can then 50 open, coming against its upper seat 26. Thus, passage 18, which leads to chamber 8 is opened, whereas ball 19, through its being applied against seat 26, prevents fuel from leaking between push piece 20 and the wall of its housing provided in body 1. As the section of passage 18 is much 55 greater than that of jet 17 provided in the delivery conduit 16 of the pump, it is evident that practically the whole of the fuel discharged by

the pump as a consequence of the stopping of the engine is returned to chamber 8. I thus avoid the difficulties that would otherwise be experienced for subsequently starting the engine. Furthermore, as long as the engine is stopped, the driver can operate at will the throttle pedal without causing the pump to discharge fuel, which is desirable if it is desired to start the engine without difficulty, when said engine is still warm.

Fig. 2 shows another embodiment in which push-piece 20 is operated by displacement in a direction opposed to that of Fig. 1. In other words, in this case, when throttle 2 is brought close to the idling position, push-piece 20 is moved downwardly, against the action of spring 21, by arm 25 when the latter is rotated in the direction of arrow B.

Fig. 2 shows the parts in the position corresponding to the opening of throttle 2 beyond the position close to the idling position above referred to. In this case, ball 18 is applied by a spring 27 against its seat 28 provided at one end of the by-pass conduit 18 leading to the constant level chamber. Communication is thus cut off with said chamber 8 and the fuel present in the pump is discharged into the induction passage of the carburetor through conduit 16¹. When throttle 2 is brought sufficiently close to its closed position, arm 25 pushes rod 22 in the downward direction, together with push piece 20 and passage 18 is opened.

Advantageously, the inlet of the pump discharge conduit 16¹ is disposed opposite seat 28 and at a distance thereof such that, when ball 19 leaves its seat 28 under the action of push piece 20, it is applied against a seat 29 provided on the inlet of delivery conduit 16¹. In this way, I obtain a double effect, since ball 19 opens the communication with constant level chamber 8 while it simultaneously closes the delivery conduit 16¹ of the pump and vice-versa. It follows that the whole of the fuel discharges by the pump when the engine is stopped is returned to chamber 8.

In a general manner, while I have, in the above description, disclosed what I deem to be practical and efficient embodiments of the present invention, it should be well understood that I do not wish to be limited thereto as there might be changes made in the arrangement, disposition and form of the parts without departing from the present invention as comprehended within the scope of the appended claims.

What I claim is:

1. For use in connection with an internal combustion engine, a fuel reservoir chamber, means forming an induction passage leading to said engine and throttle means for controlling said passage, an accelerating pump which comprises, in combination, pumping means operative in response to pressure variations in said induction passage on the downstream side of said throttle means, fuel delivery means leading from said pumping means to said passage, fuel discharge means leading from said pumping means to said fuel reserve chamber, and means operatively connected with said throttle means for instantaneously opening said discharge means and simultaneously closing said fuel delivery means when said throttle means is closed beyond a position close to the idling position and closing said discharge means while simultaneously opening said fuel delivery means when said throttle means is opened beyond said first mentioned position.

2. For use in connection with an internal combustion engine, a source of fuel, means forming an induction passage leading to said engine and a throttle for controlling said passage, an accelerating pump which comprises, in combination, a pump body, a fuel delivery conduit leading from said body to said passage, a pumping member movable in said body in response to pressure variations in the part of said induction passage on the downstream side of said throttle, a fuel return conduit leading from said pump body to said source of fuel, and valve means operatively connected with said throttle for simultaneously instantaneously opening said return conduit and closing said delivery conduit when said throttle is closed beyond a position close to the idling position and simultaneously closing said return conduit and opening said delivery conduit when said throttle is opened beyond said first mentioned position.

3. In a carburetor including a fuel reserve chamber, an induction passage to the engine and a throttle, the combination of an accelerating pump responsive to pressure variations on the downstream side of said throttle for effecting an increase in fuel flow to said induction passage in response to a given drop in intake suction, fuel delivery means leading from said pump to said passage, fuel discharge means leading from said pump to said fuel reserve chamber, and means operatively connected with said throttle for instantaneously opening said discharge means and simultaneously closing said delivery means when said throttle is closed beyond a position close to the idling one and closing said discharge means while simultaneously opening said delivery means when said throttle is opened beyond said first mentioned position.

4. In a carburetor including an induction passage to the engine and a throttle, the combination of an accelerating pump responsive to pressure variations on the downstream side of said throttle for effecting an increase in fuel flow to said induction passage in response to a given drop in intake suction, fuel delivery means leading from said pump to said passage, fuel discharge means leading from said pump to a point outside of said induction passage, and a valve operatively connected with said throttle for instantaneously opening said discharge means and simultaneously closing said delivery means when said throttle is closed beyond a position close to the idling one and closing said discharge means while simultaneously opening said delivery means when said throttle is opened beyond said first mentioned position.
